UNITED STATES PATENT OFFICE.

WALTER H. BILLINGS, OF ARLINGTON, MASSACHUSETTS, ASSIGNOR TO MILTON CHEMICAL COMPANY, OF CAMBRIDGE, MASSACHUSETTS, A CORPORATION OF MASSACHUSETTS.

DUST-MOP.

1,096,488.

Specification of Letters Patent. Patented May 12, 1914.

Application filed July 25, 1913. Serial No. 781,076.

To all whom it may concern:

Be it known that I, WALTER H. BILLINGS, a citizen of the United States, residing at Arlington, county of Middlesex, Commonwealth of Massachusetts, have invented certain new and useful Improvements in Dust-Mops, of which the following is a specification.

This invention relates to mops and particularly to a self feeding oil mop in which the oil supply is contained in a reservoir. In mops of this type one of the chief problems involved is the disposition of the mop fill so as to present the maximum mopping surface while at the same time insuring a uniform distribution of oil to all parts of the mop fibers. To the end therefore of providing a reservoir mop having a uniform oil distribution and a maximum mopping surface effectively disposed at all times, I have devised my present invention. In it I secure uniform oil feed by clamping the mop fibers between their ends within an oil reservoir of which the clamp forms the side wall and along which fibers toward both ends thereof the oil feeds by capillary action so as to thoroughly impregnate the entire mop. With the mop thus clamped the maximum mopping area is presented to the floor or other surface to be polished.

The construction and manner of assembling my improved mop will be more fully disclosed in the specification which follows and as illustrative of the same I have shown in the annexed drawings an embodiment which has been found well adapted to practical use and the requirements of manufacture.

Throughout specification and drawings like numerals of reference will indicate corresponding parts and in these drawings: Figure 1 is a central section through a mop in accordance with my invention, the reservoir parts being shown on a somewhat exaggerated scale. Figs. 2 and 3 are detail views of the top and bottom walls respectively of the reservoir detached, and Fig. 4 is a detail view of the clamping band for holding the mop fill between the top and bottom walls of the reservoir, said band also forming the side wall of the reservoir.

The mop fill is preferably of yarn or some similar fibrous material having long unbroken fibers 1 which are drawn through a clamping band 2 which engages the fibers

between their ends and preferably near their centers. This band in addition to its clamping function serves as the side wall of an oil reservoir. It is therefore sufficiently spaced from the bottom concave wall 3 and the top convex wall 4 of the reservoir to leave annular spaces 5 and 6 of sufficient width to receive the mop fibers which are inserted thereinto from one end so as to have peripheral lodgment upon the band at or near their centers. Both walls are pierced by holes in which a rivet 7 is set up uniting them in superimposed relation.

The bottom wall 3 has spaced about its periphery a plurality of upturned lips 8 adapted to engage the mop fibers and hold them clenched against the band 2 in proper disposition. The top wall 4 is similarly provided with downwardly extending prongs 9 of sufficient length to substantially overlie the band 2 and clench the mop fibers over the upper edge thereof. The clenchers of both walls, therefore, coöperate to firmly lodge the mop fibers over both edges of the clamping band and hold them symmetrically about the reservoir. This insures a uniform distribution of oil to both ends of each fiber, each fiber gradually taking up the oil toward its ends as it is required. The reservoir thus formed is supplied with oil through a feed opening 10 having a swinging cover 11 pivoted at 12 to the upper face of the top wall 4. The capacity of this reservoir is just sufficient to keep the mop properly saturated as the oil is taken off from its fibers by use or by washing. The mop may therefore be maintained in a proper condition of treatment by simply refilling the reservoir with suitable oil, of a non-spontaneously combustible nature.

To secure an even bearing for the handle so that it may rigidly support the reservoir I press up the metal of the top wall along three sides as indicated at 13. This leaves the fourth side as an angularly disposed bearing wall 14 pierced to receive a threaded bolt 15 the head 16 of which is locked against the under face of the wall by the tongues 17 formed by pressing down the metal of said wall. This bolt threads into a nut 21 set in the bore 18 of a mop handle 19 and held in place by the ferrule 20.

Considerable importance is attached to the disposition of the clamping band 2 which not only serves to clamp the mop fibers but

also forms the side wall of the reservoir. It is also important to note that the mop fibers are clamped over and find backing against both the upper and lower edges of the clamping band throughout its entire circumference. This insures not only a uniform distribution of oil but presents the maximum mopping surface possible.

Various modifications in the form and details of construction of my invention within its scope may obviously be resorted to within the limits of the appended claims.

What I therefore claim and desire to secure by Letters Patent is:—

- 15 1. In a mop of the class described, a mop fill and a reservoir comprising a side wall, over which wall the fibers of the fill are lodged between their ends and clamping top and bottom members having their margins 20 overlying said mop fill.
2. In a mop of the class described, a mop fill and a reservoir comprising a side wall, over which wall the fibers of the fill are lodged between their ends and clamping top 25 and bottom members having their margins overlying said mop fill and provided with clenchers engaging in the mop fill.
3. In a mop of the class described a reservoir having a continuous side member, a 30 mop fill disposed over both edges of said

side member and clamped thereon with its ends freely exposed.

4. In a mop of the class described a mop fill and a liquid reservoir comprising a continuous side wall over which the fibers of the mop fill are lodged between their ends, and coöperating inclosing walls effectively disposed to clamp said fill about said side wall.

5. In a mop of the class described, an 40 open ended frame, a mop fill disposed with its fibers across said frame and a pair of clamped walls forming with said frame a reservoir and said walls having said frame and fill lodged therebetween with the free 45 ends of said fill exposed.

6. In a mop of the class described, a pair 50 of reservoir forming members and a stranded mop material clamped between the margins of said reservoir members and exposed between its ends internally of said reservoir and having its free ends protruding externally thereof.

In testimony whereof I affix my signature in presence of two witnesses.

WALTER H. BILLINGS.
